UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FILLING CLAMPING AND PARTING MEANS FOR LOOMS.

1,409,314.

Specification of Letters Patent. Patented Mar. 14, 1922.

Application filed July 16, 1921. Serial No. 485,155.

To all whom it may concern:

Be it known that I, ALONZO E. RHOADES, a citizen of the United States, resident of Hopedale, county of Worcester, State of

5 Massachusetts, have invented an Improvement in Filling Clamping and Parting Means for Looms, of which the following description, in connection with the accompanying drawing, is a specification, like 10 characters on the drawing representing like parts.

This invention relates to automatic filling replenishing looms wherein the running filling is replenished prior to complete exhaustion and wherein the old or spent filling is parted between the cloth and the shuttle by a clamping and parting means mounted upon a carrier, such as the usual swinging shuttle feeler, so as to be moved bodily 20 rearwardly and forwardly or toward and from the lay.

The object of the invention is to provide a construction in which the operation of the filling clamping and parting device is 25 secured by a striker arm movable with the filling carrier support commonly provided in this type of loom and which acts to close the filling clamping and parting device when in operative position and which is yieldingly 30 movable with respect to the filling carrier support upon the occurrence of any abnormal resistance.

The object of the invention is further to provide a construction of this character in 35 which the striker arm is mounted in a housing on the side of the filling carrier support and which thus presents a simple and effective construction which may readily be added to existing looms.

40 These and other objects and features of the invention will appear more fully from the accompanying description and drawings and will be particularly pointed out in the claims.

45 The drawings illustrate the invention as embodied in a preferred form in the well known Northrop type of automatic filling replenishing loom. The invention in some respects is an improvement upon the construction illustrated and described in my prior application No. 469,599, filed May 14, 50 1921.

In the drawings:

Fig. 1 is a transverse section of a portion 55 of an automatic filling replenishing loom

with a preferred form of the present invention embodied therein, only those parts being illustrated which are necessary to the disclosure of the invention.

Fig. 2 is a view similar to Fig. 1 with 60 many of the parts therein shown omitted and showing the filling clamping and parting device in position ready to be closed upon the filling.

Fig. 3 is a front end elevation partially in 65 vertical cross section of the construction shown in Fig. 2.

The construction and operation of the automatic filling replenishing loom herein illustrated being well known and familiar 70 to those skilled in the art, it will be necessary to describe in detail only those features and their operation immediately concerned with the present invention.

The loom frame 1 supports the magazine 75 or hopper 2 containing the supply of fresh filling carriers herein shown as bobbins 3. When the running filling in the shuttle 4 on the lay 5 has become substantially exhausted, indication of that fact is transmitted 80 through a well known mechanism to the rod or rock shaft 6 which is thereupon rocked to raise the arm 7 and swing the shuttle feeler 8 rearwardly and at the same time to raise the dog 9 connected to the transfer 85 10 into the path of a bunter 11 on the lay. If the shuttle is properly boxed, allowing the shuttle feeler to pass the end of the shuttle, then the bunter 11 striking the dog 9 swings the transfer 10 downwardly 90 forcing a fresh filling carrier 3 from its position in the magazine down onto the lay, and in this case into the shuttle 4 there beneath, simultaneously ejecting the substantially exhausted filling carrier from the lay. 95

When the fresh filling carrier is in the magazine 2 ready for transfer, it rests against an abutment 12 and over a support 13 pivoted at 14 in the magazine frame so that, in order to pass out from the magazine, this support 13 must be swung downwardly about its pivot. This filling carrier support 3, which is a familiar device in this type of loom, is rigidly connected to the pivot 14 which extends to the front or opposite side 100 of the magazine and is there provided with an upwardly extending arm 15. This arm is provided with a notch 16 fitting over a pin 17 and resting against the head 18 of the pin. This pin slides through a notched or 105 110

2
slotted lug 19 projecting from the magazine 2 and a helical spring 20 surrounds the pin between this lug and its opposite head 21. Thus the pivoted or swinging support 13 is 5 normally held in the position illustrated but may move or swing downwardly against the tension of the spring 20 when the transfer of the fresh filling carrier takes place. It is this device which is utilized to secure the 10 operation of the filling clamping and parting device when, and only when, a fresh filling carrier is transferred from the magazine to the lay.

The shuttle feeler 8 acts as a carrier for 15 the filling clamping and parting device. In the form illustrated the movable blade or member 22 of this device is pivoted at 23 to the shuttle feeler and swings upwardly at its rearward or effective end to close upon the 20 co-operating elements of the device and clamp and part the filling. The rearward end of the shuttle feeler is also at its lower edge beveled or inclined upwardly as shown at 24 to insure the filling, extending from the shuttle to the fell, being guided into the 25 field of action of the filling clamping and parting device.

The general operation is a familiar one. Upon the call for filling replenishment, the 30 shuttle feeler 8 is swung rearwardly, the movable blade 22 is swung to open position, the filling clamping and parting device passes over the filling extending from the substantially exhausted filling carrier to the 35 fell. The movable blade is then swung to closing position parting and clamping the filling, and then when the shuttle feeler swings forwardly the clamped end of the 40 filling is carried forwardly so as to bring the filling into the path of the usual temple thread cutter.

The present invention is concerned particularly with the means for closing the filling clamping and parting device.

45 A housing 25 is rigidly secured to the side of the arm 15 which forms a part of the filling carrier support 13. This housing is held in place by a screw 26 passing through its lower flanged portion into the arm 15 and a 50 fulcrum stud 27 passing through the housing and screwed into the arm 15. An L-shaped striker arm 28 is pivotally fulcrumed on the stud 27 with its rearward end located in the housing and its forward and laterally extended end 29 projecting over the movable blade 22 of the filling clamping and parting device when that device is in its rearward operative position. An adjustable stop in the form of a set screw 30 held in place by 55 a lock-nut 31 extends through the top of the housing and abuts the rear end of the striker arm 28. A longitudinally acting helical spring 32 is enclosed in the housing and seated at its lower end on the housing and 60 at its upper end in a socket formed in a lat-

erally projecting lug 33 integral with the rear end of the striker arm 28. This helical spring 32 thus acts yieldingly to hold the rearward end of the striker arm against the stop 30. The striker arm is thus enabled to 70 yield against the tension of the spring with respect to the support upon the occurrence of any abnormal resistance. It is not an easy matter to assemble and adjust the filling clamping and parting device, the shuttle 75 feeler, transerrer, etc. relatively to each other, and this yielding feature of the striker arm enables any inaccuracy in adjustment to be compensated for by the relative yielding of the striker arm and filling carrier support in the closing operation of the filling 80 clamping and parting means. The closing movement of the blade 22 is usually limited by a pin 34 projecting laterally from the shuttle feeler through an opening 35 in the movable blade. After the movable blade 85 has been closed to cause the pin 34 to engage the wall of the opening 35, any further movement might act to break or shear off the pin, but such further movement is prevented in this case by the yielding of the 90 striker arm.

In order to secure the opening of the filling clamping and parting device when it moves rearwardly to operative position, a 95 switch cam mechanism is provided. For this purpose a bracket arm 36 secured to the loom frame extends upwardly and forwardly and at its upper end is provided with a stud 37 and a stop lug 38. The switch cam is in 100 the form of an inclined flange 39 formed on the rearward end of an arm 40 pivoted on the stud 37 normally resting by gravity on the lug 38. The movable blade 22 of the 105 filling clamping and parting device is provided with a laterally projecting pin 41 and the parts are so arranged that when the shuttle feeler swings to forward position, carrying the clamped and parted filling end, this pin rides beneath the switch cam 39 110 raising the arm 40, which drops back onto the lug 38 after the pin has passed forward of it, to the position shown in Fig. 1. When upon the call for filling replenishment the shuttle feeler swings rearwardly, 115 the pin 41 rides upon the forward face of the switch cam and swings the movable blade 22 to open position.

The invention thus provides a simple and effective means for securing the desired results in which the striker arm and its connected parts form a self-contained structure which may readily be connected to existing looms.

Having thus described my invention, what 125 I claim as new and desire to secure by Letters Patent, is:

1. An automatic filling replenishing loom comprising a lay, a replenishing magazine for the fresh filling carriers, means for trans- 130

ferring a fresh filling carrier from the magazine to the lay, a filling clamping and parting device movable into position to receive the running filling when the lay is in position for transfer, a filling carrier support moved by a fresh filling carrier upon its transfer from the magazine to the lay, a housing secured to the side of the support, a striker arm pivotally fulcrumed in the housing and thus bodily movable with the support and having its forward end normally projecting over the filling clamping and parting device when the said device is in its rearward operative position, a stop on the housing limiting the downward movement of the striker arm with respect to the support, a longitudinally acting helical spring mounted in the housing and interposed between the housing and the striker

arm and acting yieldingly to hold the striker 20 arm against the stop, the said striker arm thus moving with the support and acting to close the filling clamping and parting device when in operative position but yielding against the action of the spring with respect 25 to the support upon the occurrence of any abnormal resistance.

2. An automatic filling replenishing loom having the construction defined in claim 1 in which the portion of the striker arm extending into the support is provided with 30 a socket extending transversely thereof and transversely of its fulcrum axis to form a seat for the helical spring.

In testimony whereof, I have signed my 35 name to this specification.

ALONZO E. RHOADES.
